CLAIM

The ornamental design for a earring shield, as shown and described.

DESCRIPTION

FIG. 1 is a first perspective view of a earring shield showing my new design;

FIG. 2 is a second perspective view thereof;

FIG. 3 is a front plan view thereof;

FIG. 4 is a rear plan view thereof; and,

FIG. 5 is a side plan view thereof.

The broken line showing of a human head is for illustrative purposes only and forms no part of the claimed design.
